UNITED STATES PATENT OFFICE

BERNICE HARDY JOHNSON, OF BOULDER, COLORADO

BOOK

Application filed December 23, 1927. Serial No. 242,027

This invention relates to books, and more particularly to a book especially adapted for use by public readers, speakers, and other persons having occasion to refer to booklets or pamphlets dealing with various subjects.

In public recitals and readings, particularly the latter, it is desirable for the speaker or reader to have readily available a collection of articles or stories from which a selection may be quickly made to suit the particular occasion. It is the present practice for persons who deliver public readings to have such a collection in a permanently bound book. This is objectionable in that, of a collection of a number of articles or stories, but one or two may be suitable for the use of the reader. In the teaching of dramatics and in public reading, as a general rule, the instructor or reader uses one or several articles or stories which are particularly suitable for the subject under consideration or for the purpose for which the reading is given. To locate these selections in a permanently bound volume containing many other selections which the reader does not use frequently entails considerable loss of time. In addition, it is frequently necessary for the reader to purchase a completely bound volume of a large number of articles or stories for the sole purpose of acquiring but one or two stories which the reader is desirous of using. To avoid this objection it has been proposed to publish short stories or articles for use by public readers in pamphlet form. These pamphlets or booklets can be placed in a suitable binder and arranged in any desired order so as to be available. The objection to this practice is that the pamphlets are bound separately and when placed in a binder to form a series or collection, difficulty is experienced in quickly turning the leaves of the individual pamphlet or booklet.

I have found that the above objections to the present practice can be overcome by providing a booklet which contains one subject or story and which is so assembled that, preliminary to placing the booklet in a loose leaf binder, the leaves of such booklet can be readily separated so that, when a plurality

of these booklets are mounted in a loose leaf binder they form a truly loose leaf collection, the individual leaves of which may be readily turned and yet the leaves are properly grouped so that those relating to one subject matter or one story are arranged together in proper sequence, the various groups being separated by suitable title pages indicating the title or subject matter of the respective groups, which originally formed the individual booklet. To accomplish this result I temporarily bind or secure together the leaves, including the cover sheets of the individual booklets in what I term "tearable manner," that is, in such a manner that the bound portions of the leaves may be readily torn off, thus leaving the leaves separate from each other. These booklets are preferably suitably perforated to be inserted into a loose leaf binder of suitable type. Further objects and advantages of my invention will appear from the detail description.

In the drawings:

Fig. 1 is a plan view of a book constructed in accordance with my invention closed and partly broken away;

Fig. 2 is a fragmentary sectional view through the book open, the cover members being broken off and parts being shown in elevation;

Fig. 3 is a plan view of a booklet constructed in accordance with my invention showing the manner in which the bound portions of the leaves may be torn off to separate the same;

Fig. 4 is a section taken substantially on line 4—4 of Fig. 3;

Fig. 5 is a plan view of a modified form of booklet open at its center showing the manner of separating the leaves by tearing them apart; and

Fig. 6 is a section taken substantially on line 6—6 of Fig. 5.

In accordance with my invention I provide a plurality of articles or stories which are printed in the form of individual pamphlets, each pamphlet having a suitable cover sheet bearing the title of the article or story, as illustrated in Fig. 3. The leaves of this pamphlet, including the cover

100

leaf, are secured together by a suitable temporary binding which is adapted to permit ready separation of the leaves for insertion into a loose leaf binder. In Figs. 3 and 4 I have shown the leaves 1 and the cover leaves 2 as secured together by stitching 3. The stitches comprising the line of sewing or stitching 3 are short and disposed closely adjacent so as to provide a line of perforations extending from the top to the bottom, that is, from end to end, of the booklet, this sewing being disposed adjacent the inner or rear edges of the leaves of the booklet. The booklet is also preferably provided, inside of the line of sewing, with a plurality of perforations 4 disposed and adapted to receive securing rings 5 of a loose leaf binder 6 of known type, the covers 7 of which effectively enclose and protect the leaves of the various pamphlets. The rings 5 are normally held closed under spring pressure but may be readily opened to permit insertion of the leaves of a booklet as a group or unit. The binder itself is of known construction and need not be illustrated or described in detail.

By my invention, the various articles or stories may be printed in individual booklets and these booklets may be placed in the loose leaf binder. Preliminary to placing the booklet in the binder the rearward portion of the booklet is torn off by tearing along the line of the stitching or sewing 3 as indicated in Fig. 3. The group of leaves comprising the booklet is held together by the hand, after tearing off the portion 8 and is then inserted as a unit into the binder in its proper position, as indicated in Fig. 2, the rings 5 of the binder being opened and inserted through the perforations in the leaves of the booklet, after which these rings are closed in a known manner. The individual booklets are thus inserted into the loose leaf binder as units or groups of leaves, the leaves of each unit or group being arranged in proper sequence and relating to one story or subject, these groups of leaves or units being separated from each other by the cover leaves 2 of the respective booklets. These groups or units of leaves may be arranged alphabetically or in any other desired manner, the various groupings or sections of the complete book being indicated by suitable tabs projecting beyond the margin thereof, or in any other suitable manner, if desired. This renders it possible for the instructor or reader to arrange in readily available form a collection of booklets or pamphlets particularly suitable for the reading or instruction given and avoids the necessity of buying a permanently bound volume of a large number of stories only a few of which are of use to the purchaser. By this arrangement, I also avoid the objection previously referred

to, of difficulty in turning the leaves such as occurs where permanently bound booklets are assembled in a binder of the character illustrated. By tearing apart or separating the leaves of the individual booklet before inserting the same into the binder, all of the leaves of the completed book are separate from each other and may be quickly and easily turned upon the rings 5 so as to lay flat and in position to be easily read.

In Figs. 5 and 6 I have illustrated a modified form of booklet in which the leaves 9 are formed by folding centrally a sheet of paper of a width corresponding to twice the width of the leaf 9. These sheets of paper are then secured together at the fold or crease of the booklet by a line of sewing 10, the stitches of which are short so as to provide a line of perforations extending from end to end of the booklet as in the form illustrated in Figures 3 and 4. The leaves 9 of this booklet are readily separated by tearing them apart along the line of sewing, as indicated in Figure 5 and the resulting group or unit of separate leaves is then inserted into the binder in its proper position in the manner previously described.

In its broader aspects, my invention comprehends the provision of a plurality of articles or stories printed in the form of individual pamphlets or booklets, the leaves of which are initially secured together in such manner as to permit the same to be readily separated, these booklets after separation of the leaves thereof being inserted in units in a suitable binder, the respective units being separated from each other by the cover leaves thereof, as will be clear from Fig. 1. While I prefer to secure the leaves of the individual booklets together by sewing as illustrated, which I find to be very efficient for the purpose and inexpensive, I do not limit myself to this one method of securing the leaves as other means may be employed for securing together the leaves of the booklets in such manner as to permit ready separation thereof before insertion of the booklet as a unit into the binder.

Preferably, the front cover sheet or leaf 2 of each of the booklets *b* is provided with an integral tab 2^a bearing a letter or index character corresponding to the title of the article or composition, such as a musical composition, printed in the booklet. This facilitates arranging the various selections in the binder in proper order, as well as in quickly locating a desired selection.

What I claim is:—

1. As a new article of manufacture, a booklet comprising a plurality of leaves secured together by a line of sewing extending from top to bottom of the leaves and the holes made by the sewing providing a line of close perforations which facilitates ready separation of the leaves by tearing along the

line of sewing, said line of sewing constituting the sole means for securing the leaves together, said leaves having openings adjacent the line of sewing and disposed between the line of sewing and the free edges of the leaves, the portions of the leaves between the line of sewing and the free edges of the leaves being otherwise free of perforations or openings which would tend to weaken them.

2. As a new article of manufacture, a booklet comprising a plurality of leaves formed from single sheets folded upon themselves, the leaves being secured together by a line of sewing extending along the fold of the booklet and the holes made by the sewing providing a line of close perforations which facilitates ready separation of the leaves by tearing along the line of sewing, said line of sewing constituting the sole means for securing the leaves together, each sheet being provided with openings at opposite sides of the line of sewing adapted for reception of securing elements of a binder for binding together all of the sheets as a unit after tearing apart thereof and in flatwise relation, all of the leaves being otherwise free from perforations or openings which would tend to weaken them.

30 In witness whereof, I hereunto subscribe my name this 20th day of December, 1927.
